UNITED STATES PATENT OFFICE.

GEORGE M. KOHLER, OF SYRACUSE, NEW YORK.

WATER-TUBE STEAM-BOILER.

1,082,597.

Specification of Letters Patent. Patented Dec. 30, 1913.

Application filed September 10, 1912. Serial No. 719,663.

To all whom it may concern:

Be it known that I, GEORGE M. KOHLER, a citizen of the United States, and residing at Syracuse, in the county of Onondaga and State of New York, have invented certain new and useful Improvements in Water-Tube Steam-Boilers, of which the following is a specification.

The figure shown in the drawing is a sectional side elevation, showing my improved water tube steam boiler.

The object of my invention is to produce a steam boiler having the following important features: 1st: A large percentage 15 of the heating surface so arranged as to receive heat directly from the fire by radiation without the necessity of having more than one flue gas outlet. 2nd: A large combustion chamber and furnace at the front 20 end of the boiler, having no firebrick arches, with a bank of tubes so arranged as to protect the walls of the furnace from the intense heat of the fire. 3rd: The heating surface, as well as the path of the gases and 25 that of the water, in such relation with each other as to secure the maximum thermal head, insuring the attainment of the lowest possible temperature of escaping gases. 4th: A bank of tubes, with mud and feed 30 drum, void of water circulation and subject to low temperature, for the deposition of scale and sediment from the feed water.

Referring to the figure, it is seen that my boiler is of the N shape type, having an upper front steam and water drum 1, an upper rear steam and water drum 2, lower front water drum 3, lower rear water drum 4, feed and mud drum 5. These drums are parallel with each other. Their diameter 40 and length depend upon the size of the boiler. The drums are transverse of the setting, and extend from one side wall of the setting to the other side wall. The drums 1 and 2 are connected to each other by a bank 45 of steam tubes 16, and a bank of water tubes 17. Drum 4 is connected to drum 1 by a bank of either curved or straight tubes 7, drum 4 is also connected to drum 2 by a bank of either curved or straight tubes 10, thus forming a V shaped superheater space 8, in which can be placed, and connected to the steam drum, and outlet pipes, any form 50 of standard superheater 9. Drum 3 with the bank of tubes 6 is placed in the position 55 shown for two reasons,—1st: to increase the boiler heating surface in such a manner that

will enable a large amount of heat to enter the tubes by direct radiation from the fire and furnace wall. 2nd: to protect the front wall of the combustion chamber from excessive heat and consequent large loss of heat by radiation.

In order to cause a definite and rapid circulation of water in the bank of tubes 6, I employ a baffle wall 14 placed between the tubes in the manner shown. This baffle wall protects one or more rows of tubes in bank 6 from the heat of the gases. The contents of the tubes exposed to the gases consists of part water and part steam, while the 70 contents of the protected rows of tubes is all water,—hence a rapid circulation takes place in the direction shown by the arrows 18. In addition to the circulation produced, the baffle wall 14 protects the front wall 15 from the heat of the furnace gases. In this manner radiation losses from the boiler setting is greatly reduced and a thinner front wall can be installed.

Another very important and novel feature 80 of my boiler is the arrangement of the feed and mud drum 5, with the bank of tubes 11 connecting this drum with the rear steam and water drum 2. The feed water is fed into the drum 5 and rises very slowly through the 85 bank of tubes 11, thence to drum 2. The gases from the furnace, after they have passed over the tubes 6 and 7, superheater 9, and tubes 10, pass downwardly over the tubes 11, while the water in the tubes 11 90 flows upwardly in an opposite direction. This is a great advantage, for since the gas and water flow in opposite directions, the maximum thermal head is secured, which gives maximum efficiency of heat transmission. Furthermore, it is seen that the coldest feed water comes in contact with the gases just as they are about to leave the boiler setting. This enables a lower flue gas temperature to be attained than is possible 95 with any other arrangement of heating surface. A still greater advantage of this feed drum is the fact that the entering feed water is not heated by, nor does it come in contact with any steam or water from the hotter 100 parts of the boiler. The water in the feed drum is not in circulation, nor does it come into contact with steam or hot water as in all other types of multiple drum and series 105 pass boilers. The feed water is heated by 110 means of the gases which have passed over the steam generating surface of the boiler.

The velocity of the rising feed water in tubes 11 is very low, as all tubes are heated uniformly, and hence no circulation is produced in this bank of tubes. Due to the low 5 velocity of the water, the scale and sediment which is precipitated as the water is heated, is deposited on these tubes or in the mud drum. This is a great advantage, as it prevents scale from accumulating in the tubes 10, 7, or 6. These tubes are subjected to high 15 temperatures and would become a source of danger if scale were allowed to accumulate in them to even a slight thickness.

The figure shows my boiler fitted with an 15 inclined grate stoker 20, placed at the front of the boiler. If found convenient or desirable this stoker, or any other stoker, could be placed at either or both sides of the boiler. The position of the fire in relation to the tubes gives a very large combustion chamber for the efficient combustion of the fuel. Another still more important feature of the arrangement of the grate 21 and tubes is the very large amount of direct 20 heating surface available for the absorption 25 of heat by radiation from the fire and the furnace wall. This I consider a very important feature and advantage of this boiler. For one square foot of direct heating surface 30 can absorb and transmit to the water as much heat as ten to fifteen square feet of heating surface, which can absorb heat only by contact with the hot gases.

I desire to call attention to the fact that 35 there is no connection between the drums 4 and 5, as in some other boilers having two lower drums. Also that while my boiler has an A shaped combustion chamber, it has a furnace opening at the front only and 40 does not have the disadvantage of two flue gas outlets. Furthermore, my boiler has a much larger direct heating surface and a smaller amount of furnace wall subjected to 45 the intense heat of the fire than any other water tube boiler yet invented which has only a single furnace and one flue gas outlet.

I claim:

1. A water tube boiler of the N shaped type, having a furnace and combustion 50 chamber at the front end, a pair of spaced transverse steam and water drums, said steam and water drums being connected to each other by an upper bank of steam tubes and a lower bank of water tubes, a pair of 55 lower spaced front and rear water drums, each of said water drums being connected by separate banks of tubes to one of the aforesaid steam and water drums in such 60 manner as to inclose an A shaped furnace space, and the rear water drum being also connected by another separate bank of tubes to the rear steam and water drum in such

manner as to inclose a V shaped superheater space, substantially as described.

2. A water tube boiler of the N shaped type having a furnace wall and a combustion chamber at the front end thereof, a pair of spaced transverse steam and water drums, said steam and water drums being connected to each other by an upper bank of steam tubes and a lower bank of water tubes, a pair of lower spaced front and rear water drums, each of said water drums being connected by separate banks of tubes to the front steam and water drum in such manner as to inclose an A shaped furnace space, and the rear water drum being also connected by another separate bank of tubes to the rear steam and water drum in such manner as to inclose a V shaped superheater space, 75 a feed and water drum connected by banks of tubes to the rear steam and water drum, and a baffle wall separating the aforesaid bank of tubes from that bank of tubes connecting the rear water drum to the rear steam and water drum, substantially as described.

3. A water tube boiler comprising a wall, a lower front water drum, an upper front steam and water drum, a bank of tubes longitudinally positioned adjacent said wall and connecting said drums, a baffle plate placed transversely between said tubes and extending longitudinally thereof substantially the entire length of said bank of tubes 95 with a row of said tubes positioned between said baffle plate and wall.

4. A steam boiler comprising a wall, two upper steam and water drums, a large lower water drum, pipes connecting said water drum to said steam and water drums forming a V shaped superheater space therebetween, a small lower water drum, rows of inclined tubes positioned adjacent to the front wall of the boiler and connecting said smaller lower water drum and the other one of said steam and water drums, a baffle plate longitudinally positioned between said tubes with one row of tubes between said baffle and the boiler front wall, a lower feed water inlet drum, substantially vertical pipes connecting said feed water drum to one of said steam and water drums, all of said pipes and tubes arranged in the path of the products of combustion 110 and said feed water drum positioned adjacent to the outlet therefor.

In testimony whereof I affix my signature in presence of two witnesses.

GEORGE M. KOHLER.
